DESIGN FOR A ROOFING OR SIDING

Jack J. Batell, Crete, Ill.

Application December 22, 1936, Serial No. 66,684

Term of patent 14 years

To all whom it may concern:

Be it known that I, Jack J. Batell, a citizen of the United States, residing at Crete, in the county of Will and State of Illinois, have invented a new, original, and ornamental Design for a Roofing or Siding, of which the following is a specification, reference being had to the accompanying drawing, forming part thereof,

What I claim is:

The ornamental design for a roofing or siding substantially as shown.
